His Attorney.

UNITED STATES PATENT OFFICE.

RALPH L. BEACH, OF EAST ORANGE, NEW JERSEY, ASSIGNOR TO GENERAL ELECTRIC COMPANY, A CORPORATION OF NEW YORK.

LAMP-PROTECTOR.

1,250,770.

Specification of Letters Patent. Patented Dec. 18, 1917.

Application filed May 9, 1916. Serial No. 96,334.

To all whom it may concern:

Be it known that I, RALPH L. BEACH, a citizen of the United States, residing at East Orange, county of Essex, State of New Jersey, have invented certain new and useful Improvements in Lamp-Protectors, of which the following is a specification.

Many fragile articles such as incandescent lamps and similar articles have some particularly delicate part, like the tip of an incandescent lamp, which is especially liable to injury by slight blows or rough handling. The methods commonly used for packing such articles do not provide ample protection for such parts, except at comparatively great expense.

The object of my invention is to provide a simple and inexpensive support or protector which can be cut as a flat blank from paper stock or paste board, requires no paste, and when in position furnishes ample protection for the delicate parts of the article. Another object is to provide a support or tip protector which is especially suitable for incandescent lamps, requires very little skill to use and firmly supports the article in the box or carton in which it is packed. To this end, I cut from flat paper or other suitable stock a blank suitably shaped to form a shield or protector for the delicate part of the object and provided with depressions or perforations to coöperate with and grip the fragile object where it is rugged and capable of sustaining the shocks and strains incident to shipping and handling. In some cases, I make lines of weakness on the blank to facilitate bending it into the proper form.

The lamp or fragile article is packed in a carton or box, in which the support or tip protector is inserted and forms a firm support which grips the sides of a lamp, for example, and covers the tip without touching it, so that the tip is thoroughly shielded by the support or tip protector. This blank is so shaped that when in place in the carton its free edges are firmly held in place and supported by the walls of the carton to hold the blank in firm gripping engagement with the lamp.

My invention will best be understood in connection with the accompanying drawing in which merely for purposes of illustration I have shown some of the various forms in which my invention may be embodied and

in which Figure 1 is a plan view of one form of tip protector or support for an incandescent lamp; Fig. 2 is a side view of the tip protector in place upon the lamp; Fig. 3 is an end view at right angles to the plane of Fig. 2; Fig. 4 is a view in perspective with part of the carton broken away and showing the tip protector when the lamp is packed in its carton; Fig. 5 is a plan view of a modified form of the blank shown in Fig. 1; Fig. 6 is a view of one way of locking the base of the lamp in place in the carton.

In the particular form of packing shown in Fig. 1 each lamp, particularly if it is large and heavy, is packed in a separate box or carton, as shown in Fig. 4. Usually these boxes are square, but they may be made of any shape and with any number of sides. Even though the lamp fits tightly in the box it may move lengthwise of the box and if it does, the tip may be injured. To prevent injury to the tip I provide a tip protector or lamp support which is positioned in the box, as shown in Fig. 4 to firmly engage and grip the lamp near the tip and support the lamp so firmly in the box that longitudinal movement toward the tip and injury to the tip is prevented. Where the box is of the usual construction with four sides at right angles to one another, as a matter of convenience I prefer to make the support or tip protector separate and distinct from the blank of which the box is made, although it could be formed as a part of and remain attached to said blank, if desired. The tip protector when made separate is preferably in the form of a flat blank, usually rectangular in outline, as shown in Fig. 1, and transversely weakened in the middle along a line 10, so that the two ends can easily be bent toward each other to form a pair of jaws 11 for gripping the sides of a lamp. Each of these jaws is so shaped that when the support is in place it will firmly grip the bulb of the lamp and support it so as to prevent the tip of the lamp coming into contact with the sides or bottom of the box. I prefer to shape each jaw 11 so that it can fit around and grip firmly some part of the bulb of the lamp. One way to attain this result is to provide each jaw with an aperture or depression 12. The width of the blank for the protector is such that when folded it 110

will fit snugly in the box. For a four sided box the width of the blank along the line 10 is approximately the same as the length of a diagonal from one corner of the box 5 to another, so that when the blank is folded it will fit snugly into the two diagonally opposite corners and will be held against movement.

The blank is very easily inserted in the box when folded along the line 10. The lamp or similar article is then put into the box, entering between the jaws of the protector and spreading them out until their upper or free edges are against the walls of 15 the box and the lamp is firmly gripped and supported with the tip spaced away from the bottom of the box. The configuration of the blank for the tip protector depends upon the kind of box with which it is to be 20 used and is such that the jaws 11 conform along their free edges to the shape of the walls of the particular style of box selected so that the free edges of the jaws are firmly supported throughout their length. For a 25 four sided box this result may be attained by making the outline of the blank either rectangular, or hexagonal, as shown in Fig. 5. To insure that the upper edges of the jaws 11 will be supported throughout their 30 length by the walls of the box, I provide the blank with other lines of weakness to facilitate the bending of the jaws 11 into the proper form. For example, where a four sided box having flat walls and square 35 corners is used, I provide a rectangular blank with lines 13 extending diagonally from the ends of the line 10 across the corners of the jaws 11 so that these corners will bend to form wings 14 which stiffen 40 the jaws and strengthen them against bending when they grip the sides of the lamp bulb. The free edges of the jaws 11 along the lines 13 lie against and are held in 45 gripping position by the flat sides of the box, while the wings 14 lie practically flat along the box wall and reinforce the jaws 11.

Where the material of the blank is sufficiently heavy the stiffening action of the wings is not required and in that case they 50 may be omitted, the blank then, as shown in Fig. 5, being cut along the lines 13 instead of being merely weakened. In this case the blank is hexagonal in outline, instead of rectangular, its edges being formed 55 by the lines 13. As shown in Fig. 4, when the lamp is in place in the box it is firmly supported by the tip protector and the tip is fully protected. The lamp is preferably 60 locked in the box so that it cannot move when the box is handled. In the preferred construction as shown in Fig. 4 the box is made of such a length that when the base 65 of the lamp lies in one of the upper corners of the box and the box is closed, the lamp is locked by the cover of the box and

cannot be moved. The lamp may also, as shown in Fig. 6, be locked in place by means of a notch 15 in the cover, which grips the base when the cover is in place to close the box.

Although I have shown and described my invention more particularly with reference to incandescent lamps, it is of general utility in packing and shipping fragile articles, particularly those which have tips, 75 handles, or similar projecting portions that are easily injured. My invention may also be embodied in other forms than those herein disclosed, and I desire to cover all changes and modifications within the spirit 80 of my invention and the scope of the appended claims.

What I claim as new and desire to secure by Letters Patent of the United States, is,—

1. An incandescent lamp package comprising a protective shell for the lamp and a tip protector comprising hinged coöperating jaws shaped to grip and support the bulb of the lamp with its tip free of the jaws and shell, said jaws having free edges 90 which throughout substantially their whole length conform to the shape of the walls of said shell and are in firm contact with said walls to hold said jaws in place upon the lamp.

2. A package for fragile articles comprising a shell for the article and a support for insertion in the shell comprising a blank of a width to fit snugly in the shell and provided with a line of weakness to facilitate 100 bending of said blank into coöperating jaws having flat portions perforated to form supports for engaging said body at different points and brought into gripping position on said body by insertion in said shell and 105 shaped to have free edges which throughout substantially their whole extent conform to and engage the walls of the shell.

3. A support for fragile bodies inclosed in a shell having four flat walls comprising 110 a flat blank of a width to fit snugly in said shell and having a transverse line of weakness in the middle to permit bending said blank to form two hinged jaws, each of which when in place forms a di-hedral angle 115 with the bottom of the shell and a tri-hedral angle with two walls, said blank also having other straight lines of weakness extending at acute angles from said transverse line to define free edges for said jaws so shaped 120 that substantially all the edges and ends of said jaws rest against the flat walls of the shell when said support is in place.

4. An incandescent lamp package comprising a poly-hedral shell and a support 125 formed from a blank having a line of weakness to permit folding said blank along said line into a V shaped support with flat coöperating jaws for gripping and supporting the lamp near the tip, said blank having 130

along said score line a width equal to a transverse diagonal of said shell and having other score lines extending at an angle from the ends of said transverse line to define free edges of a shape to be firmly supported throughout their length by the walls of said shell when said support is in place.

5. A support for a bulbular article inclosed in a fourwalled shell with square corners comprising a rectangular blank equal in width to the distance diagonally across the bottom of said housing and transversely scored at the middle to permit said blank to fold into a pair of jaws and diagonally scored from the ends of said transverse score across each corner to form free edges which engage and are supported by the flat walls of said shell, each of said jaws being provided in the flat portion between said score lines with an aperture to receive and support a part of the article in the shell.

6. A package comprising a shell having four flat walls for inclosing the article to be packed and a flat blank adapted to be folded into a V-shaped support and inserted in said shell, said blank being perforated on opposite sides of the fold to engage said body at opposed points and hold it out of contact with the bottom of the support, the flat sides of said support being shaped to cause their edges to conform to and be held in position by the flat walls of the shell.

7. A support for articles inclosed in a flat walled shell comprising a blank scored

at the middle to permit folding to form a 35 pair of flat jaws for gripping said article and shaped at the ends to cause said jaws when inserted in the shell to be supported along substantially all their free edges by the walls of the shell, said blank being perforated to provide in each jaw an aperture to receive and support a part of the article. 40

8. A support for articles inclosed in a shell comprising a pair of jaws shaped to engage and support opposite sides of the article 45 and having a hinged portion wide enough to extend across the shell and fit snugly therein to prevent end play of said hinged portion and with their free edges so shaped that substantially all said free edges rest firmly 50 against the walls of the shell when said support is in place in the shell with the article between said jaws.

9. A support for articles in a shell with four flat walls, consisting of a rectangular 55 blank having a transverse line of weakness at its middle and four straight lines of weakness extending diagonally across the corners to form from each corner of the blank a flat tab which lies flat against the 60 walls when said support is in place, said blank being perforated on each side of said transverse line and between said diagonal lines.

In witness whereof, I have hereunto set 65 my hand this sixth day of May, 1916.

RALPH L. BEACH.
